(57) **CLAIM**

The ornamental design for a holder for calendar leaves, as shown and described.

DESCRIPTION

FIG. 1 is a front perspective view of a holder for calendar leaves showing our new design;

FIG. 2 is a front side view thereof;

FIG. 3 is a left side view thereof;

FIG. 4 is a right view thereof;

FIG. 5 is a rear view thereof;

FIG. 6 is a top view thereof; and,

FIG. 7 is a bottom view thereof.

The broken line showing of portions of the holder for calendar leaves is included for the purpose of illustrating that the holder has no specific width and forms no part of the claimed design.
